UNITED STATES PATENT OFFICE.

EZRA S. HOYT, OF LOS ANGELES, CALIFORNIA; R. C. HOYT, EXECUTOR OF SAID EZRA S. HOYT, DECEASED, ASSIGNOR TO HOYT HEATER COMPANY, A CORPORATION OF CALIFORNIA.

COIL-WINDING MACHINE.

Application filed April 5, 1923. Serial No. 629,991.

To all whom it may concern:

Be it known that I, EZRA S. Hoyt, a citizen of the United States, and resident of Los Angeles, in the county of Los Angeles and State of California, have invented new and useful Improvements in Coil-Winding Machines, of which the following is a specification.

This invention relates to a device for winding coils and is especially adapted for winding coils of metallic tubing.

Helical coils of drawn copper tubing are commonly used for water heaters, and it is desirable to quickly and efficiently wind a tube into a coil of the desired pitch and diameter without crushing or mutilating the tube. This invention has for its primary object a provision for a machine which will accomplish the above mentioned objects. In addition to the broader object of this invention, there are certain details of design and structure, whereby a simple, durable, and efficient machine, easy of operation is obtained.

25 The nature and scope of the present invention will be apparent from the subjoined specification, taken in connection with the embodiment of the invention illustrated in the accompanying drawing, in which:

30 Fig. 1 is an elevation of a fragment of a machine for winding a coil, only those portions on the machine essential to the present invention being shown; Fig. 2 is a section as seen on the line 2—2 of Fig. 1; and Fig. 3 is a perspective view of the travelling collar.

Referring more particularly to the drawing, the elements of the structure as illustrated herein are shown as forming a portion of a lathe structure, wherein 3 indicates the bed. Mounted upon the bed is a front bearing 4 carrying a shaft having secured thereto a cone pulley 5. Connected to the cone pulley so as to be driven there- 45 by is a mandrel 6. The mandrel is cylindrical in form and has a semi-circular helical groove 7 formed therein. The diameter of the mandrel at the bottom of the groove is the internal diameter of the coil to be wound, the groove corresponding to the convolutions of the coil. The groove extends over the entire length of the mandrel. Secured to one end of the mandrel is a block 8 having a groove in its under surface 50 complementary to the groove in the man-

drel and registering with the latter when secured in position. The block serves as a clamp and is conveniently secured to the mandrel by means of a cap screw 9.

60 A travelling collar 10 is slidably mounted upon the mandrel, it having a lug 11 arranged to travel in the groove 7. An extension 12 supports a stub shaft 13 upon which is mounted a trolley wheel 14. The trolley wheel is grooved complementary to the groove 7 and is disposed to roll over the surface of the mandrel. The space formed between the groove in the trolley and the groove in the mandrel is substantially circular in transverse section and 70 equal to the external diameter of the tube to be wound. The trolley wheel is so disposed with relation to the lug 11 that it will register with the groove 7 on the mandrel. A leg 15 extends laterally from the 75 collar and is diametrically opposite to the extension 12. The leg is of sufficient length to ride in the well or way formed in the bed, as best illustrated in Fig. 2.

80 The stock to be wound comprising a tube indicated by 16 in Fig. 1, is clamped to the mandrel at one end by means of the block 8. The collar 10 is disposed with the trolley wheel 14 over the tube. The mandrel 6 is then rotated so as to cause the collar to travel toward the free end. The collar is impelled to travel longitudinally of the mandrel with the trolley wheel always in registration with the groove and advancing toward the free end of the mandrel. 90 The tube 16 is forced into the groove 7 by the trolley wheel. When the collar has completed its travel over the mandrel, it disengages itself from the latter, whereupon rotation of the mandrel is stopped. The 95 block 8 is then released from the tube and the adjacent ends of the latter lifted by means of a tool. The mandrel is then rotated in the reverse direction so as to unscrew the coil from the mandrel.

100 The simplicity of the machine and the ease of operation are apparent from the foregoing description.

What I claim is:

1. A coil winding machine comprising a rotatable mandrel having a helical groove in its surface, said mandrel having means to detachably secure the stock in said groove at one end thereof, a travelling collar having a complementary grooved member ex- 105 110

tending from one side thereof and registering with said helical groove, said collar embracing said mandrel and engaged with said groove, said mandrel forming a guide for said collar, and means to prevent rotation of said collar but permit longitudinal movement thereof.

2. A coil winding machine comprising a rotatable mandrel having a helical groove in its surface, said mandrel having means to detachably secure the stock in said groove at one end thereof, a travelling collar having a grooved trolley wheel mounted at one side thereof and registering with said helical groove, said collar embracing said mandrel and engaged with said groove and being of such width that said mandrel forms a guide therefor, and means to prevent rotation of said collar but permit longitudinal movement thereof.

3. A coil winding machine comprising a rotatable mandrel having a helical groove in its surface, said mandrel having means to detachably secure the stock in said groove
25 at one end thereof, a stationary way extending parallel to the axis of said mandrel, a travelling collar having a complementary groove member extending from one side thereof and registering with said helical groove, said collar having a leg resting against said way whereby to prevent rota-
30

tion of said collar but to permit longitudinal movement thereof.

4. A coil winding machine comprising a rotatable mandrel having a helical groove in its surface, said mandrel having means to detachably secure the stock in said groove at one end thereof, a stationary way parallel to the axis of said mandrel, a travelling collar having a complementary grooved trolley wheel mounted upon one side thereof, and registering with said helical groove, and a leg resting against said way whereby to prevent rotation of said collar but permit longitudinal movement thereof. 45

5. A coil winding machine comprising a rotatable mandrel having a helical groove in its surface, said mandrel having means to detachably secure the stock in said groove at one end thereof, a stationary way parallel to the axis of said mandrel, a travelling collar having a lug engaged in said groove, a complementary groove trolley wheel mounted upon the side of said collar and registering with said helical groove, and a leg on said collar resting against said way whereby to prevent rotation of said collar but permit longitudinal movement thereof.

In witness that I claim the foregoing I have hereunto subscribed my name this 30th day of March, 1928. 60

EZRA S. HOYT.
